UNITED STATES PATENT OFFICE

122,584

DESIGN FOR A COMBINED PERFUME BOTTLE AND STOPPER THEREFOR

Emma O. Douglas, Honolulu, Territory of Hawaii, assignor to Harders Company, Limited, Honolulu, Territory of Hawaii

Application June 25, 1940, Serial No. 93,244

Term of patent 7 years

To all whom it may concern:

Be it known that I, Emma O. Douglas, a citizen of the United States of America, residing at Honolulu, in the county of Honolulu and Territory of Hawaii, have invented a new, original, and ornamental Design for a Combined Perfume Bottle and Stopper Therefor, of which the following is a specification, reference being had to the accompanying drawing, forming a part thereof, wherein,

I claim:

The ornamental design for a combined perfume bottle and stopper therefor, substantially as shown.

EMMA O. DOUGLAS.
